HAMILTON K. BOYD, OF PITTSBURGH, PENNSYLVANIA, ASSIGNOR OF ONE-HALF TO
ERNEST H. OHLENDORF, OF MIMS, FLORIDA.

GAS-HEATER.

1,228,289.

Specification of Letters Patent. Patented May 29, 1917.

Application filed July 14, 1916. Serial No. 109,313.

To all whom it may concern:

Be it known that I, HAMILTON K. BOYD, a citizen of the United States, residing at 32 East General Robinson street, Pittsburgh, 5 in the county of Allegheny and State of Pennsylvania, have invented a new and useful Gas-Heater, of which the following is a specification.

The present invention relates to an improvement in gas heaters designed to be used to heat cold air and discharge the heated air into the same room in which the heater is located, the room being thereby heated by the air as well as by the heat directly radiated from the heater.

It is the object of the present invention to provide among other features a heater which is constructed of a number of detachably connected plates, peculiarly arranged 20 to provide large heat radiating surfaces and an air flue to protect the plates, and in which is heated a large volume of air; also a heater wherein the flame will not "roar" when the gas is admitted under full pressure to the burner and which is highly 25 efficient consuming substantially one-third less fuel than prior heaters; and which requires practically no attention after the burner is lighted.

Other objects and advantages of this invention will be brought out in the following specific description of the present preferred embodiment, the same being illustrated in the accompanying drawings, 30 wherein—

Figure 1 is a front elevation of a gas heater constructed according to this invention.

Fig. 2 is a vertical transverse section, 40 taken through the same.

Fig. 3 is a top plan view of the gas heater, the top being removed.

Fig. 4 is a horizontal section, taken on the line 4—4 of Fig. 2.

Fig. 5 is a detail perspective view of the upper deflecting plate.

Fig. 6 is a detail perspective view of the lower deflecting plate.

The heater of this invention is preferably 50 made up of a plurality of plates or sheets, which are detachably secured together to permit the renewal of the sheets or plates when burnt out, and to permit the ready cleansing of the interior of the heater.

10 are the side plates, which extend upwardly at the opposite sides of the heater, and which are of a width equal to the depth of the heater. The forward and rear edges of the side plates 10 are rolled over inwardly toward each other, to provide locking beads or flanges 11. 12 and 13 are upper and lower bottom plates, respectively, which are vertically spaced apart between the lower ends of the side plates 10, and are secured thereto by means of flanges 14 and 15 turned downwardly from the opposite ends of the bottom plates 12 and 13. The upper bottom plate 12 extends rearwardly from the forward edges of the side plates 10, and is inclined upwardly at a slight angle, 70 as shown in Fig. 2. This bottom plate 12 terminates short of the rear edges of the side plates 10, and is rolled upwardly and over at its rear edge to provide a locking bead 16. The forward edge of the upper 75 bottom plate 12 has a downturned flange 17 adapted to fit against the inner side of a lower front plate 18, which extends across the front of the heater at the bottom thereof. The opposite ends of the front plate 18 80 are rolled over for engagement in the lower ends of the front locking beads 11 of the side plates 10. The upper edge of the front plate 18 is preferably bent inwardly to overlap the forward edge of the upper bottom 85 plate 12, and the flange 17 is suitably secured to the front plate 18.

The lower bottom plate 13 extends from the rear edges of the side plates 10, forwardly and downwardly, and terminates 90 short of the forward edges of the plates 10 to provide, behind the front plate 18, a bottom passage or opening through which air may pass or circulate from beneath the stove. The bottom plates 12 and 13 provide a substantially horizontal air duct or 95 flue A in the bottom of the heater. A back plate 19 has its opposite edges rolled over for interlocking engagement with the rear locking beads 11 of the side plates. The 100 back plate 19 extends from the top to the bottom of the stove, and is preferably provided, near its upper end, with an outwardly extending nipple 20 to which may be attached a conducting pipe for carrying off 105 the products of combustion from the heater.

A second back or fire plate 21 is arranged in forwardly spaced relation to the back

plate 19, and has its lower edge rolled over for interlocking engagement in the bead 16 of the upper bottom plate 12. This second back plate rises from the rear end of the bottom plate 12, and is inclined forwardly at a slight angle. The back plates 19 and 21 provide a vertical air duct or passage B, which is a continuation of the passage in the bottom of the heater. The 10 second back plate 21 is rolled over at its upper edge to provide a locking bead 22.

The stove is provided with a pair of spaced apart, forwardly and upwardly extending, deflecting plates 23, and 24. The lower 15 deflecting plate 23, shown in detail in Fig. 6, has its lower edge rolled over and interlocked with the bead 22 of the back plate 21, and comprises substantially a continuation of the back plate. The deflecting plate 23 has flanges 25 at its opposite ends, which are secured against the inner faces of the sides 10. The upper forward end of the plate 23 has a depending flange 26, which is secured against the inner side of an upper 20 front plate 27, the latter having its opposite ends rolled over and interlocked with the front beads 11 of the side plates. The lower deflecting plate 23 has its opposite forward corners cut away to provide 25 passages 28 immediately behind the front plate 27, and at the opposite sides or ends of the heater.

The upper deflecting plate 24, shown in detail in Fig. 5, has an upturned flange 29 35 on its rear end, which is secured against the back plate 19. The upper deflecting plate 24 has its opposite lateral edges converging forwardly, and has, at its forward end, an upturned flange 30, which is secured against the rear side of the front plate 27. The opposite converging edges of the deflecting 40 plate 24 have depending flanges 31, which extend downwardly to, and rest at their lower edges upon, the upper face of the lower deflecting plate 23. Outturned flanges 32 extend along the lower edges of the flanges 31, and are adapted for securement upon the upper face of the lower deflecting plate 23. The flanges 32 have notches 33, as shown in Figs. 3 and 5, to register with the 45 passages 28 in the plate 23. The lateral flanges 31 lie flat against the side plates 10 at the rear end of the deflecting plate 24, and are cut away at their lower edges, to 50 accommodate the locking bead 22 of the second back plate 21.

The front plate 27 is provided with an outlet opening D therethrough, which registers with the duct or passage C between the deflecting plates 23 and 24, permitting air, rising through the duct, to pass out through the front of the heater. A reinforcing plate 34, of any adaptable design and size, is suitably secured against the 60 front plate 27, and has an opening therein

which registers with the outlet opening in the front plate.

A baffle plate 35, is placed, substantially vertically, in the heating chamber, formed in the upper end of the shell above the deflector plate 24. This baffle plate 35 terminates, at its lower end, in spaced relation from the deflecting plate 24, to provide a passage about the lower end of the baffle plate through which the products of combustion may pass as they are carried to the outlet nipple 20. This baffle plate 35 is provided at its opposite ends with flanges 36, secured against the inner faces of the sides 10. A top 37 is fitted over the shell, and has its marginal edge overturned beneath the top, and projected downwardly to provide an inwardly offset flange 38, which extends into the shell and lies against the inner faces of the adjacent plates. As shown, 85 the flange 38 is provided with a plurality of slots 39, which open through the lower edge of the flange, and which are adapted to receive therein clamping bolts, or the like, to detachably hold the top in position. 90

The flanges of the various plates are preferably held in place by nuts and bolts, so that the plates may be separated when it is desired to renew them, and to permit the easy assemblage of the parts in setting up 95 the heater.

A burner tube 40 extends longitudinally through the heater preferably over the inner end of the upper bottom plate 12. The tube 40 has a row of gas outlet openings 41 100 in its upper side, through which the gas may issue. The upper bottom plate 12 is provided with a row of air inlet openings 42, arranged preferably immediately behind the burner tube 40, and at the base of the forward or second back plate 21. Air passes from the bottom air duct A up through the openings 42, and promotes the thorough combustion of the gas which issues from the burner tube. 105

Legs 43, or the like, are detachably secured to the lower corners of the shell, to support it in spaced relation from the floor or ground, and permit a circulation of the air upwardly through the duct. 110

When the burner is lighted, the flame plays against the back or fire plate 21, and the deflecting plate 23. Air is drawn upwardly through the air duct A leading through the bottom of the shell, upwardly in the duct B between the backs of the shell, and further upwardly and forwardly in the duct C between the deflecting plates 23 and 24, the air being heated by contact with the bottom plate 12, the back plate 21, and the upper deflecting plates 23 and 24. This heated air passes outwardly through the opening D of the upper front plate 27 into the room to be heated. The products of combustion are thoroughly burned by the 120 125 130

admixture of air therewith, which passes upwardly through the openings 42 behind the burner tube 40. The products of combustion pass upwardly against the deflecting plate 23, are caught behind the front plate 27, and pass through the passages 28 into the heating chamber at the top of the shell.

The baffle plate 35 traps the products of combustion in this heating chamber, and thus obtains the benefit of practically all of the heat units for heating the walls of the chamber. The upper deflecting plate 24 is, in this manner, maintained at a high temperature, while the heat from the combustion chamber heats the bottom plate 12, the back plate 21 and the lower deflecting plate 23, and the air in the duct is thoroughly heated in its passage upwardly through the heater. The heat in the combustion chamber is deflected outwardly, through the open front of the shell, by the plates 12, 21 and 23.

The second back plate 21 may be provided with a layer of asbestos, or the like, and the sides 10, the bottom 12, and the deflecting plate 23 may be covered with a layer of copper, as shown in the drawings. The baffle plate 35 may be provided with openings 44, (Fig. 3) which are out of line with the outlet nipple 20, to provide a circuitous path for the products of combustion, and thus prevent the easy flow of the same outwardly through the shell. By thus trapping the products of combustion the walls of the heating chamber in the top of the shell are thoroughly heated.

What is claimed is:-

1. A gas heater comprising a shell formed of side plates, a top plate and a back plate connected to the top and side plates, an upwardly inclined deflecting plate connected to the back plate and the side plates below the top plate, and a front plate connected to the upper end of the deflecting plate thereby forming a heating chamber which is defined by the back, front, top and deflecting plates, said back plate having an opening near the top, a baffle plate depending from the top plate and arranged to extend below the opening of the back plate, a second back plate and a second deflecting plate each spaced from the first mentioned back plate and deflecting plate to provide an air duct which is open at the bottom for the ingress of cold air, and a burner arranged in front of the second mentioned back plate, the deflecting plates having registering passages formed therein at the top for the products of combustion to reach the heating chamber without escaping into the air duct.

2. A gas heater comprising an open front shell composed of side walls, a back wall joining the side walls, a bottom plate in-

clined downwardly from the back wall and terminating short of the front edges of the side walls, a top plate, and an upwardly inclined deflecting plate spaced below the top plate to provide a heating chamber in the top of the shell, a combustion chamber in the shell between said side walls composed of a second bottom plate inclined upwardly and backwardly from the front edges of the side walls and spaced from the first mentioned bottom plate to provide an air duct in the bottom of the heater, and terminating short of said back wall, a back plate rising from the rear end of the second mentioned bottom plate and spaced from the back plate to provide a continuation of the air duct at the back of the heater, a second upwardly inclined deflecting plate spaced below the first deflecting plate to provide therewith the upper end of the air duct, a front plate to which the said deflecting plates are connected, said front plate having an opening in line with the air duct, and a burner in the combustion chamber, said deflecting plates having passages therethrough leading from the top of the combustion chamber to the heating chamber.

3. A gas heater having side plates, a back plate joining the rear edges of the side plates, upper and lower front plates connecting the forward edges of the side plates, spaced apart and overlapping bottom plates of less width than the side plates and arranged between the side plates and extending one from the back plate and one from the lower front plate and providing therebetween an air duct in the bottom of the heater, a second back plate rising from the inner end of the upper bottom plate and in spaced relation to the first mentioned back plate to provide a vertical continuation of the air duct in the back of the heater, a pair of spaced apart deflector plates inclining upwardly and forwardly from the back plates to provide an upper continuation of the air duct, the upper front plate having an opening in alignment with the upper end of the duct formed between the deflector plates, and a burner arranged above the upper bottom plate, and close to the second back plate.

4. A gas heater comprising a shell having an outlet in its back, an open front combustion chamber arranged within the shell, said shell and said combustion chamber having opposed and spaced apart bottom plates, back plates and top deflecting plates to provide an air duct therethrough extending along the bottom and about the combustion chamber and opening thereabove through the front of the shell, the upper deflecting plate forming the bottom of a heating chamber in the top of the shell opening through said outlet, both of the de-

reflecting plates having a passage therethrough at the front connecting the combustion chamber with the heating chamber, a burner in the combustion chamber at the lower end thereof and at the rear, the upper of said bottom plates being provided with a series of openings between said burner and the inner one of said back plates whereby air is admitted to said burner from said air duct, and means for deflecting the

heated products of combustion along the top of the upper deflecting plate.

In testimony, that I claim the foregoing as my own, I have hereto affixed my signature in the presence of two witnesses.

HAMILTON K. BOYD.
